(57) **CLAIM**

The new design for a recessed cockpit for kayaks, as shown
and described herein.

DESCRIPTION

FIG. 1 is a perspective view of a recessed cockpit for kayaks
showing my new design;

FIG. 2 is an enlarged perspective view taken along lines
2—2 in FIG. 1;

FIG. 3 is a top plan view thereof;

FIG. 4 is a side elevational view thereof, the opposite side
being a mirror image of that shown;

FIG. 5 is a bottom plan view thereof;

FIG. 6 is an elevational view of a first end thereof; and,

FIG. 7 is an elevational view of a second end thereof.

The broken line showing of environmental structure in
FIGS. 1—7 is for illustrative purposes only and forms no part
of the claimed design.
